MANIFOLDING DEVICE

Delbert G. Dalby, Amarillo, Tex., assignor to
Roberts Paper Company, Amarillo, Tex.

Application March 30, 1946, Serial No. 658,463

9 Claims. (Cl. 197—126)

1

This invention relates to improvements in manifolding device.

The main objects of this invention are:

First, to provide a manifolding device or apparatus which may be readily incorporated in existing types of typewriting machines primarily for the purpose of facilitating the manipulation of multiple webs in association with carbon sheets.

Second, to provide a manifolding apparatus or device in which the carbon sheets are assembled as a pack and may be quickly interleaved or interspaced with the paper and supported so that the paper may be manipulated in relation to the carbon sheets in a manner greatly expediting the work.

Third, to provide a means for releasably supporting a carbon pack in operative relation to the paper and the platen which is highly effective and at the same time quickly operated to secure or release the carbon sheets.

Fourth, to provide a device having these advantages which is very compact and economical in structure and may be readily embodied in the form of an attachment to be applied to typewriting machines now in extensive use.

Objects pertaining to details and economies of the invention will appear from the description to follow. The invention is defined in the claims.

A structure embodying the features of the invention is clearly illustrated in the accompanying drawing, in which:

Fig. 1 is a fragmentary perspective view of a typewriting machine embodying my invention, the machine proper being illustrated conventionally and in more or less skeletonized form.

Fig. 2 is a perspective view of the carbon pack and web guide device of my invention embodied as an attachment for a machine of the type illustrated.

Fig. 3 is an enlarged fragmentary view partially in longitudinal section on a line corresponding to line 3—3 of Fig. 4.

Fig. 4 is an enlarged fragmentary vertical section on a line corresponding to line 4—4 of Fig. 1 including the platen of the typewriting machine.

Fig. 5 is a fragmentary view partially in section corresponding to Fig. 3 showing the carbon pack clamp in open position, it being shown in closed position in Fig. 3.

Fig. 6 is a fragmentary perspective view of the rockshaft and one of the clamping rollers.

Fig. 7 is a fragmentary perspective view of the carbon pack illustrating its relation to the multiply paper webs, a part of the carbon sheets

2

being folded back to illustrate that they are free at one edge.

Fig. 8 is an enlarged fragmentary view in section on line 8—8 of Fig. 7.

In the accompanying drawing 1 represents a typewriting machine. 2 is the platen of the machine and 3 is the guide and supporting rollers for the webs of paper 4. As the structural details of the machine form no part of my invention and as my invention is capable of adaptation or embodiment in various types of machines, I do not illustrate or describe the details of the machine herein.

In the embodiment of the invention illustrated 15 I provide an auxiliary frame designated generally by the numeral 5 and adapted to be mounted on the carriage frame of the typewriting machine. The auxiliary frame comprises end members 6, 6, a front cross bar or member 7, and a rear cross bar or member 8. The end members are provided with supporting brackets 9 having thumb screws 10 by means of which the auxiliary frame is mounted on the cross bar or member 11 of the carriage frame. The end members 6 of the auxiliary frame are downwardly offset at 12 so that the front member 7 is positioned above and fairly close to the platen.

The front member 7 constitutes a clamping bar or member for the carbon pack and is desirably a flat piece disposed vertically edgewise. On the inner side of the member 7 I mount a rockshaft 13, the journals 14 of which are eccentrically disposed as shown in Fig. 5. The rockshaft is provided with a crank 15 at its right hand end by means of which the rockshaft may be rotated and thereby swung to and from the clamping member 7 as clearly shown in Figs. 3 and 5. The parts are in actuated position in Fig. 3 and in retracted position in Fig. 5. A stop 20 16 is provided to limit the forward stroke of the lever which is the retracting stroke.

The rockshaft is provided with a pair of clamping members designated generally by the numeral 17. In this preferred embodiment these 45 clamping members are in the form of resilient rollers 18 rotatably mounted on the sleeves 19 between the flanges 20 of the sleeves and the retaining collar 21. The sleeves are fixed to the rockshaft, at least anchored against longitudinal 50 movement thereon.

I provide a carbon pack designated generally by the numeral 22 which consists of a plurality of carbon sheets 23 having laterally projecting integral tabs 24 and 25 on their side edges. The 55 tabs 24 are bound together by means of the flexi-

ble binding member 26 folded over the edges of the tabs 24 and secured thereto, desirably by stitching 27. The sheets are further secured by means of the pliable or flexible adhesive strips 28 which are adhered to the binding member 26 and lapped upon and adhered to the outer carbon sheets, this being clearly shown in Fig. 8. This binds the carbon sheets together as a unit at one edge only, the opposite edges of the carbon sheets being free so that they may be easily introduced between or interleaved with the webs of paper. The pack may be easily adjusted longitudinally of the webs of paper into proper position to permit clamping of the binding tab of the pack and also the free tabs into proper relation for clamping between the clamping rolls and the clamping bar. The resilient rotatable clamping members 17 are highly desirable because they minimize the liability of tearing or injuring the carbon pack.

With the carbon pack suitably clamped in operative relation to the platen as shown in Fig. 4 the webs of paper may be pulled or fed through the plies of the carbon pack in manifold relation as it will be noted that the carbon pack is clamping supported laterally of the edges of the webs. The carbon pack is secured in its adjusted position and may be released simply by shifting the handpiece 15. With the clamp members released the carbon pack may be rolled in manifold relation with the webs of paper to any desired position on the platen.

The rear cross member 8 of the auxiliary frame serves as a guiding support for the multiple webs of paper and is provided with adjustable guide members 29 slideable on the member 8 and secured in adjusted positions by the thumb screws 30. The guide members have fingers 31 which overlap the webs of paper. This guiding means is effective in keeping the webs of paper in proper lateral position in the machine and may be adjusted to accommodate paper of different widths.

In the drawing the carbon pack is illustrated as positioned in the machine with the tabs on the leading end thereof. It may be positioned in the manner illustrated or inverted—that is, positioned with the tabs at the lower edge of the pack. This arrangement has the advantage of lessening the possibility of wrinkling the sheets of the pack held by the tabs when the forms are pulled through as friction then tends to straighten out the carbon sheets and to maintain them in proper position without wrinkling and without special care in manipulation of the paper webs.

I have illustrated and described my invention in a highly practical embodiment thereof. I have not attempted to illustrate or describe various modifications and adaptations which I contemplate as it is believed that this disclosure will enable those skilled in the art to embody or adapt the invention as may be desired.

Having thus described my invention, what I claim as new and desire to secure by Letters Patent, is:

1. A manifolding apparatus including in combination the carriage frame and platen of a typewriting machine, an auxiliary frame comprising like end members and front and rear cross members, the front member being disposed beyond the platen relative to the travel of the paper over the platen and in spaced relation thereto and constituting a clamp member, the rear member being adapted to guidingly support a plurality of webs of paper and provided with adjustable guides for the paper, depending arms on said end mem-

bes having notches and set screws for releasably attaching said auxiliary frame to a cross member of said carriage frame, a rockshaft eccentrically mounted on said end members at the rear of said front member and provided with an adjusting finger piece, and resiliently faced clamping rollers rotatably mounted on said rockshaft to be actuated to and from coacting clamping relation with said front member by rotative movement of said rockshaft, said clamping rollers being spaced to releasably engage and support carbon sheets in operative relation to the platen and at points laterally spaced from the edges of the webs of paper interleaved with the carbon sheets.

2. A manifolding apparatus including in combination the carriage frame and platen of a typewriting machine, an auxiliary frame mounted on said main frame and comprising end members and front and rear cross members, the front member being disposed beyond the platen relative to the travel of the paper over the platen and in spaced relation to the platen and constituting a clamp member, the rear member being adapted to guidingly support a plurality of webs of paper and provided with adjustable guides for the paper, depending arms on said end members releasably supporting said auxiliary frame on a cross member of said carriage frame, a rockshaft eccentrically mounted on said end members at the rear of said front member and provided with an adjusting finger piece, and clamping members mounted on said rockshaft to be actuated to and from coacting clamping relation with said front member by rotative movement of said rockshaft, said clamping members being spaced to releasably engage and support carbon sheets in operative relation to the platen and at points laterally spaced from the edges of the webs of paper interleaved with the carbon sheets.

3. A manifolding apparatus including in combination a platen of a typewriting machine, a bar-like clamp member disposed beyond the platen relative to the path of travel of the paper thereover, an eccentrically mounted manually rotatable rockshaft, clamping shoes mounted on said rockshaft to be actuated to and from coacting clamping relation with said clamp member by rotative movement of said rockshaft, said shoes being spaced to lie outside of the side edges of a sheet of paper in said machine and to clamp the tabs of a carbon pack comprising a plurality of carbon sheets having laterally projecting side edge tabs to said clamp member.

4. A carbon pack holder device for typewriting machines comprising a supporting frame having like end members with depending arms removably secured to said machine, a relatively fixed clamping member carried by said frame and disposed beyond the platen relative to the travel of the paper over the platen and in operative relation thereto, a manually adjustable rockshaft mounted on said frame, and resiliently faced clamping rollers eccentrically mounted on said rockshaft to be actuated to and from coacting clamping relation with said fixed clamping member by rotative movement of said rockshaft, said clamping rollers being spaced to releasably engage and support carbon sheets in operative relation to the platen of the machine and at points laterally spaced from the edges of the webs of paper interleaved with the carbon sheets.

5. A carbon pack holder device for typewriting machines comprising a supporting frame, depending arms on the sides of said frame and removably secured to the carriage of the machine,

a relatively fixed clamping member carried by said frame and disposed on the discharge side of the platen and in operative relation thereto, a manually adjustable rockshaft eccentrically mounted on said frame, and resiliently faced clamping members mounted on said rockshaft to be actuated to and from coacting clamping relation with said fixed clamping member by rotative movement of said rockshaft, said clamping members being spaced to releasably engage and support carbon sheets in operative relation to the platen of the machine and at points laterally spaced from the edges of the webs of paper interleaved with the carbon sheets.

6. A manifolding attachment for a typewriter comprising a pair of like side members having depending arms intermediate of the ends thereof, said arms being notched at the lower ends thereof and provided with set screws for removably attaching said side members to a cross bar of a typewriter carriage frame with the forward ends of said members located along the delivery side of the platen of the typewriter, a clamp bar secured between the forward ends of said members, a rockshaft eccentrically journaled in said side members and spaced rearwardly from said clamp bar, a hand piece for rotating said rockshaft, cylindrical clamping members on said shaft and movable into and out of gripping engagement with said clamp bar upon movement of said rockshaft, a back bar supported between the rear ends of said side members, and guides for supporting the web advancing to the typewriter adjustably secured to said back bar.

7. A manifolding attachment for a typewriter comprising a pair of side members having depending arms intermediate of the ends thereof, said arms being notched at the lower ends thereof and provided with set screws for removably attaching said side members to a typewriter carriage frame with the forward ends of said members located along the delivery side of the platen of the typewriter, a clamp bar secured between the forward ends of said members, a rockshaft eccentrically journaled in said side members and spaced from said clamp bar, a hand piece for rotating said rockshaft, clamping members on said shaft and movable into and out of gripping engage-

ment with said clamp bar upon movement of said rockshaft, a back bar supported between the rear ends of said side members, and guides for supporting the web advancing to the typewriter adjustably secured to said back bar.

5 8. A manifolding attachment for a typewriter comprising a pair of side frame members having depending arms intermediate of the ends thereof, said arms being adapted to be attached to the 10 carriage of the typewriter with the forward ends of said members located along the delivery side of the platen of the typewriter, a clamp bar secured between the forward ends of said members, a rockshaft eccentrically journaled in said end members and spaced from said clamp bar, a hand piece for rotating said rockshaft, clamping members on said shaft and movable into and out of gripping engagement with said clamp bar upon movement of said rockshaft, and a back bar supported between the rear ends of said side members and operative to support a web of paper advancing to said typewriter.

15 9. A manifolding attachment for a typewriter comprising a generally rectangular frame arranged to be secured in generally horizontal position over the carriage of the typewriter, the front member of said frame being adapted to be positioned along the discharge side of the platen of the typewriter, a rockshaft journaled between the 20 side members of said frame and spaced from said front member, a hand piece on said rockshaft, and clamping members mounted eccentrically on said rockshaft movable into and out of clamping engagement with said front member upon rotation of said rockshaft.
